MULTIPOINT GAS SAMPLING MANIFOLD

Mary K. Gray, Box 33,
Sylvania, Ohio 43560

Filed Jun. 30, 1975, Ser. No. 591,527

Term of patent 14 years

Int. Cl. D23—01; D24—02
U.S. Cl. D32—1 R

Fig. 2.

Fig. 3.

Fig. 1.

Fig. 4.

Fig. 6.

Fig. 5.

FIG. 1 is a side elevation of a multiport gas sampling manifold, showing my new design;

FIG. 2 is a top plan view thereof;

FIG. 3 is a left end elevation thereof;

FIG. 4 is a bottom plan view thereof;

FIG. 5 is a right end elevation thereof; and

FIG. 6 is a side elevation with all the fittings removed for clarity of illustration.

I claim:

The ornamental design for a multiport gas sampling manifold, as shown and described.
